US00D771646S

(12) **United States Design Patent** (10) **Patent No.:** **US D771,646 S**
Chaudhri et al. (45) **Date of Patent:** **** Nov. 15, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Imran Chaudhri**, San Francisco, CA (US); **Elizabeth Caroline Cranfill**, San Francisco, CA (US); **Tiffany Jon**, Sunnyvale, CA (US); **Christopher Daryl Soli**, Mountain View, CA (US)

(73) Assignee: **Apple Inc.**, Cupertino, CA (US)

(**) Term: **14 Years**

(21) Appl. No.: **29/503,909**

(22) Filed: **Sep. 30, 2014**

(51) LOC (10) Cl. **14-04**

(52) U.S. Cl. **USPC D14/485**

(58) **Field of Classification Search**

USPC D14/485
CPC .. G06F 3/048; G06F 3/0481; G06F 3/0486;
G06F 3/049

(57) **CLAIM**

The ornamental design for a display screen or portion thereof with graphical user interface, as shown and described.

DESCRIPTION

The FIGURE is a front view of a display screen or portion thereof with graphical user interface showing our new design.

The thin broken lines around the FIGURE show a display screen or portion thereof, and form no part of the claimed design. The thin broken lines within the FIGURE show portions of the graphical user interface that form no part of the claimed design. The thick broken lines within the FIGURE show a feature of the claimed design.

1 Claim, 1 Drawing Sheet
